Primary Examiner—Gary D. Watson

(73) Assignee: **Quinta Corporation**, Congers, NY (US)

(74) Attorney, Agent, or Firm—Blank Rome Comisky & McCauley LLP

(**) Term: **14 Years**

(57) **CLAIM**

(21) Appl. No.: **29/102,808**

The ornamental design for an asymmetric module for a modular seating system, as shown and described.

(22) Filed: **Apr. 1, 1999**

DESCRIPTION

(51) LOC (7) Cl. **06-01**

FIG. 1 shows a perspective view of a first type of asymmetric module for a modular seating system according to the present invention. The second type of asymmetric module is simply a mirror image of the first type.

(52) U.S. Cl. **D6/334**; D6/368; D6/335

FIG. 2 shows a front view of the first type of asymmetric module.

(58) Field of Search D6/334, 335, 336, D6/364, 365, 368, 374, 381, 500, 501, 502; 297/232, 440.1, 440.12

FIG. 3 shows a back view of the first type of asymmetric module.

(56) **References Cited**

FIG. 4 shows a left view of the first type of asymmetric module.

U.S. PATENT DOCUMENTS

FIG. 5 shows a right view of the first type of asymmetric module.

FIG. 6 shows a top view of the first type of asymmetric module.

FIG. 7 shows a bottom view of the first type of asymmetric module; and,

FIG. 8 shows one way in which the first and second types of modules can be arranged into a modular seating system. The broken lines shown in FIG. 8 are for illustrative purposes only and form no part of the claimed design.
